UNITED STATES PATENT OFFICE.

HERBERT H. HULL, OF LAKEWOOD, OHIO, ASSIGNOR, BY MESNE ASSIGNMENTS, TO
ANCHOR CAP & CLOSURE CORPORATION, OF BROOKLYN, NEW YORK, A CORPO-
RATION OF NEW YORK.

CLOSURE FOR CONTAINERS.

1,253,491.

Specification of Letters Patent. Patented Jan. 15, 1918.

Application filed March 11, 1916. Serial No. 23,453.

To all whom it may concern:

Be it known that I, HERBERT H. HULL, a citizen of the United States, residing at Lakewood, in the county of Cuyahoga and State of Ohio, have invented a certain new and useful Improvement in Closures for Containers, of which the following is a full, clear, and exact description, reference being had to the accompanying drawings.

10 This invention is a closure for containers of glass and similar material, one object of the invention being to provide a closure which is made without a bead, and applied and sealed without a beading operation.

15 Another object of the invention is to provide a closure with straight or flat coating flange portions which remain straight or flat at all times; and another object is to provide a closure of such construction that 20 it can be applied to and securely seal containers having a considerable variation in their external diameters; and a still further object is to provide a closure which from its nature will prevent breakage of the container during the sealing operation.

Another object of the invention is to provide a closure which can be applied with equal facility and effectiveness to a container which is flaring at the top like an 30 ordinary tumbler, it being understood that the tumbler containers in use at the present time are made straight or of uniform diameter at the sealing portion.

With these various objects in view, the 35 invention consists in the features of construction hereinafter fully described and pointed out in the claims.

In the drawings forming a part of this specification, Figure 1 is a sectional view 40 of the blank from which the closure is made; Fig. 2 is a sectional view illustrating the first step in the punching or shaping process; Fig. 3 a similar view showing a second step and Fig. 4 is a vertical sectional view of the closure completed and ready to receive the rubber gasket or packing ring; Fig. 5 is a sectional view showing the closure with the rubber gasket or packing ring arranged therein and applied to the top 50 of a container and Fig. 6 is a sectional view showing the container with closure sealed thereon and dies for effecting the sealing operation.

In making a closure in accordance with

my invention I employ a disk 10, of thin 55 lacquered tin or similar material, and this disk is first punched or shaped to provide a circular cap or closure with the usual annular corrugation or upset portion 11 which is adapted to receive the upper edge of the 60 container. The cap or closure is then shaped with a surrounding angled flange comprising the outwardly and downwardly extending portion 12, and the inwardly and downwardly extending portion 14, the extreme 65 edge being rolled back upon itself as shown at 13 providing a reinforcement for the inwardly and downwardly inclined portion of the flange.

As thus constructed, the closure is provided with an angled flange, the lower or free portion of said flange being reinforced. A rubber gasket or elastic packing ring 15 is fitted into the angle of the flange and will remain thus seated without danger of dislodgment. The outwardly extending portion 12 and the inwardly extending portion 14 are both straight and flat and remain so at all times and when it is desired to seal the closure upon a container, the said closure is placed upon the top of the container 70 16, and this container with the closure thereon is placed within and between the sealing dies 17 and 18; and it will be noted that the angle or incline 19 of the die 18 is 75 exactly the same as the angle or inclination of the portion 12 but the angle or incline 20 of the die 17 is somewhat sharper than the angle or incline of the portion 14 so, that when the dies are brought together, 80 the portion 14 of the angled flange is forced upwardly and inwardly, and in so doing, the rubber gasket or packing ring is 85 squeezed into tight contact with the exterior of the container thereby effecting a perfectly tight seal. The lower or free portion 14 of the angled flange being reinforced or of double thickness, can be turned in in the manner described and will remain in such position. In view of the fact that this free 90 portion of the flange has a considerable inward movement, it is obvious that a closure constructed in this manner will readily accommodate itself to considerable variations of external diameters in containers and if 95 the reinforced portion of the flange should be forced into contact with the container 100 there will be a certain yielding due to the 105

fact that the upper portion of the flange is of less thickness than the lower portion and breakage of the container during the sealing operation is thereby prevented.

5 Under ordinary circumstances, the position of the upper portion of the flange of the closure does not change, the lower portion only moving toward the upper portion, and at the same time contracting in diameter 10 and squeezing the rubber gasket or packing ring forcibly into close contact with the exterior of the container.

15 By avoiding the use of beading tools or appliances for sealing the closure, the operation can be accomplished much quicker and easier and with less damage to both closure and container.

Having thus described my invention, what I claim is:—

20 1. In a closure for containers and the like, a cover portion, a depending rim extending at substantially right angles to said cover portion, a ring sloping downwardly and outwardly from said ring, another ring 25 angularly disposed to the first mentioned ring and sloping downwardly and inwardly, the free edge of said last mentioned ring being reinforced, and a gasket carried between said rings and adapted to be tightly compressed against the wall of a substantially incompressible container by decreasing the diameter of the free edge of the lower ring.

30 2. A closure comprising a cover portion, a rim extending at substantially right angles to the plane of said cover portion, an outwardly extending ring carried by said rim whereby an obtuse angle is formed between said rim and said ring, and a second ring 35 extending from the first mentioned ring and at an acute angle thereto, the metal of said second ring being folded upon itself to form

a reinforced free edge for said second ring, and a gasket carried between said rings and adapted to be compressed against the side wall of a substantially incompressible member by decreasing the angle between said rings and decreasing the diameter of the free edge of said second ring.

3. As an article of manufacture, a sealed package comprising a container, said container having substantially incompressible, side walls adjacent the mouth thereof, and a substantially flat cover cap extending over the mouth of said container, a skirt extending over said incompressible side walls, said skirt comprising angularly disposed rings with the free edge of the undermost ring reinforced and the area inclosed between said rings and the side wall of said container being in cross-section substantially an equi-angular triangle, and a gasket within said area and under compression.

4. As an article of manufacture, a sealed package comprising a container, said container having a substantially incompressible straight cylindrical side wall adjacent the mouth thereof, a cover member extending over the mouth of said container, a skirt extending downwardly over said straight cylindrical side wall, said skirt comprising angularly disposed rings meeting at their outer extremity to form an outwardly extending V-shaped bead whereby the area inclosed between said straight cylindrical side wall and said rings is substantially an equi-lateral triangle, and a gasket within said area and exerting substantially uniform pressure upon all sides of said area.

In testimony whereof, I hereunto affix my signature.

HERBERT H. HULL.
